176,589

ELECTRIC FRYER

Morris D. Bandler, Forest Hills, N. Y.

Application April 13, 1955, Serial No. 35,490

Term of patent 14 years

(Cl. D81—10)

The figure is a perspective view of an electric fryer embodying my new design.

I claim:

The ornamental design for an electric fryer, as shown.

References Cited in the file of this patent

UNITED STATES PATENTS

D. 173,716	Boldt	Dec. 28, 1954
D. 174,504	Krause	Apr. 19, 1955